[57] CLAIM

The ornamental design for a fluorescent lamp holder or the like, as shown and described.

DESCRIPTION

FIG. 1 is a top plan view of a fluorescent lamp holder or the like showing our new design;

FIG. 2 is a bottom plan view thereof;

FIG. 3 is a front elevational view thereof;

FIG. 4 is a rear elevational view thereof;

FIG. 5 is a side elevational view thereof; and

FIG. 6 is the opposite side elevational view thereof.

The broken line drawings of the fluorescent lamp bulbs and the terminal pins are for illustrative purposes only and part of the claimed design.
